CLAIM

The ornamental design for a galley bag, as shown and described.

DESCRIPTION

FIG. 1 is a front, right, top isometric view of a first embodiment of a galley bag showing the new design;

FIG. 2 is a front, left, top isometric view thereof;

FIG. 3 is a rear, left, bottom isometric view thereof;

FIG. 4 is a front view thereof;

FIG. 5 is a rear view thereof;

FIG. 6 is a left side view thereof;

FIG. 7 is a right side view thereof;

FIG. 8 is a top view thereof; and

FIG. 9 is a bottom view thereof.

FIG. 10 is a front, right, top isometric view of a second embodiment of the galley bag showing the new design;

FIG. 11 is a front, left, top isometric view thereof;

FIG. 12 is a rear, left, bottom isometric view thereof;

FIG. 13 is a front view thereof;

FIG. 14 is a rear view thereof;

FIG. 15 is a left side view thereof;

FIG. 16 is a right side view thereof;

FIG. 17 is a top view thereof; and,

FIG. 18 is a bottom view thereof.

The dashed lines shown in the drawings represent portions of the galley bag that form no part of the claimed design. In FIGS. 10–18, the galley bag is shown with symbolic dot-dash break lines that form no part of the claimed design. The appearance of any portion of the article between the break lines forms no part of the claimed design.

1 Claim, 18 Drawing Sheets
